UNITED STATES PATENT OFFICE

CHARLES W. GREEN, OF ILION, NEW YORK, ASSIGNOR TO REMINGTON ARMS COMPANY, INC., A CORPORATION OF DELAWARE

CASH REGISTER

Application filed December 19, 1927. Serial No. 241,046.

One of the objects of this invention is to provide improved mechanism for retaining in elevated position the operated indicator tablets in a cash register and for releasing at each operation those indicators that have been previously operated. It is a particular object of the invention to provide means whereby improper "dropping" of indicators and the erroneous retention of previously operated indicators will be effectively prevented, so that the proper indication will be displayed at all times.

It is a further object to provide means to insure that a correct indication will always be displayed even though the keys are operated quickly and with considerable force.

Another object of my invention is to provide simple and effective means for insuring against overthrow of totalizer wheels, even though the latter be subjected to operations of considerable rapidity.

In the accompanying drawings the improvements are shown in one form which they might take when applied to or embodied in machines of the type shown and described in the U. S. application Ser. No. 183,392, filed April 13, 1927, by Charles W. Green. This embodiment is only illustrative, however, as the improvements are capable of modification and change to permit applying them to machines of various types, and it is the desire not to limit the use of the improvements to any one style of register.

In machines of the key-operated type, which is the type of register used to exemplify the present invention, the tablet indicators are usually directly elevated by the keys. During the elevation of the indicators a supporting bar is first moved by the operating mechanism of the machine away from the indicators, to release the indicator tablets that were raised in the preceding operation; and said bar is then moved in the opposite direction for engaging portions of the newly elevated tablets, to retain them in elevated position.

In rapid operations of the machine the depressed keys may be returned so quickly that the related elevated indicators may be lowered to such an extent that by the time

the supporting bar has been moved to its indicator supporting position it will not cooperate with the supporting portions of the elevated indicators, permitting the latter to drop downwardly as the depressed keys are being returned to normal. It is important that said bar be moved to its supporting position before it is too late to retain the newly elevated indicators. At the same time, the supporting bar should not be restored from its position for releasing the previously elevated indicators to its indicator supporting position so rapidly as to re-engage any indicator which should not be retained.

In the preferred construction of my invention the supporting bar is, at an early stage in the operation of the machine, moved outwardly sufficiently to permit the release of the previously elevated indicators and after it has received its maximum movement it may be moved oppositely towards its normal supporting position by suitable spring means. Suitable latching mechanism is provided to hold the released supporting bar away from its normal position but quite close to the indicators. At substantially the time when the newly-raised indicators are elevated to their maximum position, the latch is disabled, permitting the spring means to further rock the supporting bar to its normal supporting position for holding said indicators in elevated position. It will be evident therefore, that by this construction the supporting bar is not returned directly to indicator engaging position, and thus its effectiveness for releasing previously operated indicators is increased; while on the other hand only a short movement of said bar is necessary to engage the newly elevated indicators, and such engagement may be quickly and promptly effected when the newly raised indicators are in position therefor.

In the preferred construction the indicators are arranged in groups, one behind the other. The stems, however, are staggered so that they may engage the rear ends of their respective keys. When the elevated indicators are disengaged from the supporting bar they may be restored to their normal po-

sition by gravity but in very rapid operations of the machine this force may not act quickly enough to cause the elevated indicators to escape the supporting bar and drop to their normal positions. This would result in retaining an undesired indicator in elevated position. To prevent mis-operations such as this, the stems of the indicators preferably carry coil springs which engage a stationary plate. Contact of one end of the spring with the plate serves to compress the spring at the extreme downward depression of the operated key and the compression stored up in the spring is effective to depress the elevated indicator initially insuring that the supporting portion of the elevated indicator will escape the supporting bar. Due to the peculiar construction of the arrangement of the indicators and the stems it is not possible to carry the coil springs directly by the stem as in the prior art constructions. The improved means of carrying the springs is simple in construction, effective in performance and greatly reduces the cost of assembling the indicators and springs.

With the above and other objects in view the invention consists in a novel combination and arrangement of parts, the features of novelty which are pointed out in the appended claims, and a preferred form of embodiment of which is hereinafter described with reference to the drawings accompanying and forming part of this specification.

Of said drawings:

Fig. 1 is a vertical transverse sectional view of the type of machine disclosed in the above-mentioned Green application with the present improvements applied thereto.

Fig. 2 is a sectional view taken on the line 2-2 of Fig. 1 illustrating particularly the arrangement of the indicator stems.

Fig. 3 is a partial top plan view of the indicating mechanism and illustrates the manner in which the indicators are grouped together.

Fig. 4 is a front elevation of the indicating mechanism showing clearly the manner in which the indicator stems are staggered and the improved spring means for initially restraining the elevated indicators.

Fig. 5 is a fragmentary top plan view showing certain of the indicator controlling parts of Fig. 1.

Fig. 6 is a fragmentary detail view in front elevation showing parts of my improved overthrow preventing means.

The general organization and operation of the mechanism as a whole having thus been outlined the preferred construction of the parts for accomplishing the above-mentioned features will now be described more in detail.

The improvements are applied to a cash register of the key-operated type in which the amount keys are divided into a plurality of banks for registering the amounts of the

several denominations. The machine also contemplates the provision of special keys, such as transaction or clerk's keys, for example, whereby special transactions or the clerk operating the machine may be suitably indicated. As will be more apparent later on, the improvements in the indicating mechanism may be applied to either amount or special indicators.

As best shown in Fig. 1, the amount keys 19 are pivoted upon a shaft 20 journaled between the main side frames 21 of the machine. The mechanism is enclosed by a suitable cabinet 22. The various keys carry at their front portions suitable key caps bearing indicia designating the nature of the keys and the forward ends of the key levers are guided by slots 23 formed in the cabinet 22. At their rear ends the keys are guided by slots 24 formed in a plate 25 secured to cross bars 26 and 27.

All the keys are provided with notches 28 adapted to receive the rearward end of a key coupler 29 which extends between the side frames 21 and normally rests upon the rear ends of the keys. The key coupler is pivotally supported by means of a pair of parallel plates 30 attached to the ends of the key coupler by screws 31. The plates 30 are suitably apertured to receive a shaft 32 which is located in substantially the mid-portion of the machine and carried by the side frames. It will be obvious that when the forward ends of the operating keys are depressed the key coupler 29 will be rocked counter-clockwise so that its rearward end will enter the notches 28 of the depressed keys. The purpose of such key coupler mechanisms is well known in the art and need not be discussed herein.

It is desirable that some device be provided to insure a complete performance of the started registration before a second operation can subsequently be effected. To this end any suitable mechanism may be provided but in the present instance one of the plates 30 (Fig. 1) is extended upwardly and to the rear to form a segment 33 provided with teeth 34 adapted to co-act with a pawl 35 to which a spring 36 is connected. Very early in the operation of the machine the engaging end of the pawl 35 will co-act with one of the teeth and thereby hold the key coupler and key in their operated positions even though pressure on the key may be released and during the subsequent portion of the down-stroke of the key the ratcheting of the pawl over the teeth will prevent any retrograde movement of the key or key coupler.

At the termination of a down-stroke of the key the full-stroke pawl will be disengaged from the rack thus permitting the restoration of the keys and the key coupler but at the same time after this return movement has

commenced will prevent movement in the opposite direction.

As will be noted in Fig. 1, the rear ends of the keys are formed with upstanding projections 37, the forward edges 38 being substantially concentric with the key coupler supporting shaft 32. When the coupler is being operated the rearward end 29 thereof will pass in front of the concentric portion 10 of the unoperated keys thereby locking them against movement. Since this construction is well known in the art it need not be discussed herein in further detail.

The present invention includes improvements in the indicating mechanism with which the machine is equipped whereby the items or classifications represented by the various keys are publicly indicated during each operation of the machine. The indicators in the present instance comprise flat tablets bearing suitable indicia, the tablets being provided with stems which directly co-operate with the rear ends of the operating keys. As best shown in Figs. 3 and 4, the indicators are arranged in groups of three so that for a full bank of nine keys there will be three adjacent groups of indicators. By this construction it will be obvious that the indicators are more nearly in the same plane than would be possible to place them if each group contained the nine tablets related to a particular denomination. Also in the event of the depression of the adjacent keys of different denominational orders one indicator will not hide the other to the same extent as if they were otherwise arranged.

The upper portions 39 of the indicators, as will be seen in Fig. 4, carry the designated characters, and the character bearing portions are integral with indicator stems 40. The indicators are confined and guided in their reciprocatory movements by having the stems fitted into slots formed in a lower supporting plate 41 which is attached to the bar 46 and an upper supporting plate 42 which is attached to a cross bar 43. It will be noted in Fig. 4 that considering the indicators of a group of three, the foremost indicator has its stem to the right of a central vertical line 59 of the group so that the stem is in the path of the rear end of its related key. Furthermore, the rearmost indicator of the same group has its stem to the left of the vertical center line so that this stem may also be in line with its related key. The intermediate indicator of the group is different in shape from the others and has its indicator stem centrally located so that it is directly in line with its related key. By this construction and arrangement it will be obvious that each indicator may be directly elevated by its associated key.

The stem 40 of each indicator is provided with a pair of centrally located rectangular slots 44 and 45 which are separated by an integral portion 46. Extending between the

side frames of the machine is an indicator supporting bar or bail 47 located forwardly of the indicators and pivoted by integral side arms 48 which are apertured to receive a shaft 49 extending transversely of the machine and journaled in the side frame 21. The bar 47 is of channel formation and the lower horizontal portion is formed with a plurality of projecting fingers 50 each of which projects through the lower rectangular slot 44 of one of the indicator stems 40. The co-operation of the lower ends of the slots 44 with the fingers 50 serves to stop the upward movement of the indicators when raised by their keys and especially to prevent any overthrow 80 movement of an indicator when the associated key is operated violently and quickly.

The upper portion of the channel bar 47 is also provided with projecting fingers 51, which as shown in Fig. 3, are of different 85 lengths. When the indicators are in their lowermost position each finger projects into the upper slot 45 of its associated indicator. However, when an indicator 39 is elevated by the associated key the related finger 51 will 90 first be drawn out of co-operation with the upper slot 45 by means which will presently be described, and will then co-operate with the lower slot 44 beneath the cross portion 46 thus holding the indicator in raised position. 95 It will be noted, therefore, that since the fingers 51 are of different lengths so as to project into the slots 44 of their related stems an equal amount, the rocking movement of the supporting bar 47 serves to disengage all the 100 fingers 51 from co-operation with the cross bars 46 at substantially the same time during the cycle of operation of the indicator releasing mechanism.

As shown in Fig. 1 one of the side arms 48 of the indicating supporting bar 47 is connected to a slidable member 52 the forward end of which is guided by a slotted stud 53 carried by the left side frame 21. The extreme forward end of the slidable member 52 105 is provided with a lug 54 in the plane of an extension 55 of the key coupler supporting plate 30. A spring 56 connected between the member 52 and a stud carried by the left side frame 21 urges the member 52 and indicator supporting bar 47 rearwardly to the position shown in Fig. 1 until stopped by an extension 110 57 integral with the left side arm 48 co-acting with the bar 43.

Pivotedly mounted on the stud 53 is a latch 115 58 provided with a hook 59 adapted to engage with a lug 60 on the upper side of the slide member 52. Connected to the latch 58 is a spring 61. It will be seen that at an early stage in the depression of a key the extension 120 55 will cooperate with the lug 54 to draw forwardly the slidable member 52 and the supporting bar 47 is thereby rocked forwardly to withdraw the fingers 51 from the slots of the indicator stems to permit the descent of 125 130

those indicators which were raised at the preceding operation of the machine. Shortly after the extension 55 engages the lug 54 to draw the slidable member 52 forwardly, the hook 59 will be disengaged from the lug 60, permitting the spring 61 to rock said hook downwardly so that the edge 66 rests upon the top of said lug 60. It will be noted that the path of movement of the extension 55 is concentric with respect to the shaft 32, while the movement of the slidable member 52 is in substantially a straight line and at the intersection of the lines delineating these two movements the extension 55 will be disengaged from the lug 54 and the member 52 released. The spring 56 now draws said member 52, together with the supporting bar 47, rearwardly, but the movement in this direction will be stopped by the coaction of the lug 60 with the hook 59. The supporting bar 47 is thus not permitted to return directly to its normal position but is held in an intermediate position wherein the retaining fingers 51 are just out of engagement with the slots in the associated indicator stems. As the depression of the key continues, the indicator associated with said key continues rising and at substantially the time that the key is fully depressed, the indicator elevated by said key will have reached its highest position, at which time the cross portion 46 of said indicator will have been positioned above the associated retaining finger 51; and when this relation exists a stud 62, carried by the plate 30, will contact with a finger 63 of the latch member 58 thereby disengaging the hook 59 from the lug 60 permitting the spring 56 to further rock the supporting bar 47 to its normal position so that the fingers 51 may pass beneath the cross portions 46 of the elevated indicators. It will thus be noted that the indicator supporting bar 47 will be finally released only when the elevated indicators have received their highest positions, at which time the cross portions 46 will be positioned above the fingers 51, and it will be further noted that said bar 47 need move but a slight distance from its latched position to indicator retaining position. Such movement of said bar 47 may thus take place in a minimum of time thereby insuring that the fingers 51 will pass beneath the portions 46 of the raised indicators before the latter start downwardly during the return movement of the depressed keys.

During the return movement of the depressed keys, the substantially horizontal edge of the extension 55 cooperating with the lug 54 will rock the slidable member 52 about its pivotal connection with the side arm 48 and the lug 60 coacting with the hook 59 will also rock the latch 58, tensioning the spring 61, and when said horizontal edge of extension 55 is completely withdrawn from

beneath lug 54 the springs 56 and 61 will return the member 52 and latch 58 respectively to their normal positions.

It has been found that in rapid operations of the keys a previously elevated indicator might be held up in its exposed position during a subsequent transaction even though the related key was not depressed. It will be seen that the time element which intervenes between the retraction of the supporting bar 47 and its final release is reduced when the keys are operated quickly and that it might not afford sufficient time to allow a previously elevated indicator to drop downwardly by gravity to its normal position. As a result this indicator may also be held elevated by the supporting bar and an erroneous indication produced.

To eliminate such mis-operations the invention includes the provision of spring means for giving each indicator an initial restoring movement, further restoration of the indicator being due to gravity. As best shown in Fig. 4, it will be noted the lower portion of the stem 40 which is beneath the slot 44 is apertured to form a pair of oppositely extending fingers 64. In assembly one end of a coil spring 65 is passed over one of these fingers and fully compressed so that the other end may surround the other finger when the compression of the spring is released. This facilitates to a great extent and reduces the time necessary to assemble the springs and the indicators particularly so in machines possessing a high registering capacity which requires a large number of indicators and springs.

It will be noted in Fig. 4 that the springs 65 are beneath the lower plate 41 with a result that when an indicator is fully elevated the spring 65 will be compressed as shown in Fig. 4, but this compressive action occurs only at the extreme downward depression of the key when a considerable amount of power is available. This lessens the load on the machine contrasting to heavier loads imposed by constructions employing springs so long that they are compressed during the entire depression of the key. When the supporting bar 47 is rocked forwardly during the beginning of the operation of the machine so as to cause the disengagement of the finger 51 with the cross portion 46 of an elevated tablet the compression in the spring 65 will be effective to start the indicator down initially quickly so that by the time the supporting bar 47 is rocked to its normal position the cross portion 46 will be considerably below the associated finger 51. In practice this expedient has been found very effective in its performance.

Fig. 2 shows the echelon arrangement of the stems 40 of the indicators and also illustrates the manner in which the springs 65 are carried by their respective stems to avoid in-

terference with each other. As a result of this arrangement it will be noted that each unit comprising an indicator stem and spring may be moved independently of and without interference with any other unit.

The operation of my improved indicator controlling mechanism may be briefly summarized as follows:

If a key in a certain bank has previously been depressed the related indicator will occupy the position shown in Fig. 1 wherein it will be noted that the cross portion 46 rests upon the related supporting finger 51. In this instance it will be noted that the upper end of the coil spring 65 is in direct contact with the plate 41 and that a force due to compression has been stored in the spring. If, for example, another key in the same denominational bank should subsequently be depressed, depression of this key will rock the key coupler 29 and, therefore, the plate 30. During the down-stroke of the operated key the extension 55 will strike the lug 54 and through the member 52 will rock the indicator supporting bar 47 about its pivotal point disengaging the finger 51 from the cross portion 46 of the elevated indicator so that the compression stored in the spring 65 will depress the elevated indicator quickly allowing it to drop to its normal position. During the continued depression of the operated key the member 52 will be rocked further forwardly resulting in a similar rocking movement of the supporting bar 47 until the lug 60 clears the hook 59, whereupon the spring 61 will be effective to rock said hook clockwise so that it is positioned to the rear of the lug 60. When the extension 55 clears the lug 54 the spring 56 will rock the member 52 and indicator supporting bar 47 rearwardly towards their normal positions until the lug 60 contacts with the hook 59 thereby stopping the rocking movement of the indicator supporting bar 47 and holding it in a partially rocked position at which time the fingers 51 are close to the stems of the related indicators. During this time the depressed key is still raising its associated indicator and at substantially the time the indicator occupies its highest position the pin 62 will contact with the finger 63 of the latch 58 disengaging the hook 59 from the lug 60 thereby permitting the spring 56 to draw the member 52 and indicator supporting bar 47 to its normal position and since the related indicator has been positioned so that the cross portion 46 is above the related finger 51 the latter will pass beneath the cross portion 46. When the operated key begins its up-stroke the indicator will descend slightly until the cross portion 46 rests upon the finger 51. The operated key may now be given an independent restoring movement and upon continued movement of the key to its normal position the extension 55 contacting with the under-

side of the lug 54 will rock the member 52 about its pivotal connection with the side arm 48 and through the lug 60 contacting with the hook 59 will rock the latch 58 in a counter-clockwise direction against the tension in the spring 61. When the extension 55 clears the lug 54 the springs 56 and 61 will force the member 52 and hook 58, respectively, to their normal positions. When the operated key is at its normal position the parts will again be in the positions shown in Fig. 1 at which time the indicator related to the last key depressed will have its indicia so positioned that it may be viewed through an aperture in the cabinet indicating to bystanders the last amount registered.

Machines of this character are at times subjected to improper usage by extremely rapid and violent operations. In rapid operations of an adding machine or cash register considerable momentum is imparted to the various elements and particularly to the actuators for the totalizer wheels as well as to said wheels themselves. It is important that the totalizer wheels be not thrown beyond their proper positions. I have devised means simple in construction but effective in operation for insuring against overthrow even though the parts be subjected to unusually forceful and rapid operation. This means is shown applied to the machine of my application Serial No. 183,392, hereinbefore referred to, but its applicability to machines of various types will be apparent.

In Fig. 1 there is shown one of a series of actuating segments 70 adapted to drive a corresponding totalizer wheel 71; it being, of course, understood that the totalizer wheels are engageable with the respective actuating segments for actuation in accordance with the keys depressed. In my application above referred to I have disclosed certain forms of means whereby the totalizer wheels may be engaged with the actuators for actuation thereby during depression of the keys. The totalizer engaging means, however, forms no part of my present invention and is hence not described herein. It is sufficient to note that the totalizer wheels are driven by the actuators during the down stroke of the keys, which is of common occurrence in the art.

Each actuating segment is movable with a corresponding differential frame 701 operated by the associated denominational series of keys 19; said frame having a rearward cross piece 702 lying in the path of upstanding extensions 191 on the rear portions of said keys whereby said frame is rocked when any of the associated series of keys is depressed. The rear extensions 191 of the respective keys are spaced different distances from the cross piece 702, whereby the differential frame may be actuated different ex-

tents, commensurate with the values of the keys. Each key is also provided with a complementary projection 192 on its forward portion, which projection is adapted to engage a cross bar 703 on the differential frame to positively stop the latter when it has been moved the appropriate extent.

While each segment 70 is secured to its corresponding differential frame, and while each differential frame is positively held against overthrow by the complementary stops 192, I have provided an additional overthrow preventing means cooperating directly with the actuating segments and precluding overthrow thereof when the register keys are misoperated by too rapid and violent depression. If, in the course of extremely rapid and forceful operations, a segment should be temporarily strained beyond its proper position and the associated totalizer wheel momentarily overthrown, an incorrect reading might under certain circumstances result. More specifically, should the proper position of the totalizer wheel be at "9", overthrowing thereof as the result of improper and violent operation might, though only momentary, result in conditioning the transfer mechanism for carrying "1" prematurely to the totalizer wheel of next higher order. To insure that misoperation of the machine shall not result in such overthrow, I have provided the following mechanism.

Each actuating segment has secured thereto a serrated plate 72. Secured to the front tie bar 73, of the machine, is a bracket 74 comprising a horizontal portion 75 and side arms 76, 77, the rear portions of said side arms being bifurcated to engage the shaft 20 for support thereby. Pivots mounted in said bracket is a bail 78 having fingers 79 extending rearwardly and adapted to cooperate with the serrated plates 72. A spring 80, interposed between said bail and an ear 81 of bracket 74 normally holds the bail in its forward position (Fig. 1), in which position a forward extension or arm 82 of said bail rests against the horizontal portion 75 of said bracket 74. Extending from the opposite side of said bail is an arm 83 carrying a laterally disposed pin 84 which lies in the path of a rocking finger 85. The latter is an extension of a segmental plate 95 which moves with the key coupler 29.

From the foregoing description it will readily be seen that as the register keys are depressed and the segments 70 operated to drive the totalizer wheels 71, the finger 85 moves downwardly, and at approximately the end of the depression of said keys said finger will strike pin 84. The fingers 79 of bail 78 are thereby brought into engagement with the serrations of extensions 72 so that the actuators 70 and totalizer wheels 71 in mesh therewith will not be carried beyond their proper positions.

The above described mechanism for preventing overthrow of the totalizer actuators has been made the subject of a divisional application, Serial Number 347,335, filed March 15, 1929.

While the form of mechanism herein described is admirably adapted to fulfill the objects primarily stated, it is to be understood that it is not intended to confine the invention to the one form of embodiment herein shown since it may be embodied in various forms, all coming within the scope of the claims which follow.

What is claimed is:

1. In a cash register, the combination of an indicator having a stem, said stem being provided with two oppositely disposed projections, and a coil spring carried by said projections.
2. In a cash register, the combination of an indicator having a stem, said stem being apertured and provided with two oppositely disposed projections, and a coil spring fitting in said aperture and surrounding said projections.
3. In a cash register, the combination of a movable indicator having a stem, said stem being apertured and provided with two oppositely disposed projections, a coil spring fitting in said aperture and surrounding said projections, and a stationary plate co-operating with said spring when said indicator is moved.
4. In a cash register, the combination of a plurality of liftable tablet indicators of a supporting bar therefor, an operating mechanism, means controlled by the operating mechanism for retracting and then releasing the indicator supporting bar, a latch for holding the released indicator bar, and means controlled by the operating mechanism for disabling the latch.
5. In a cash register, the combination of a tablet indicator, of a supporting bar therefor, an operating mechanism and means controlled by the operating mechanism for retracting said indicator bar, means for holding said bar away from its normal position, and means controlled by the operating mechanism for disabling said holding means.
6. In a cash register, the combination of a plurality of indicators, a bar adapted to releasably support the indicators, a member adapted to retract said bar, a latch for holding the bar and member in retracted position, and means for disabling the latch.
7. In a cash register, the combination of a plurality of keys, a plurality of amount indicators elevated by said keys, a bar for releasably supporting the elevated indicators, means for retracting and then holding the bar to permit the release of the previously elevated indicators and the elevation of the newly raised ones, spring means for initially depressing the previously elevated indicators,

and means for releasing the retracted bar when the indicators are elevated by the keys.

5 8. In a cash register, the combination of an indicator having a stem, and a spring disposed intermediate the side portions of said stem for urging said indicator toward its normal concealed position.

10 9. In a cash register, the combination of an indicator having a stem, a spring carried by said stem for urging said indicator toward its normal concealed position, and mounting means for said spring intermediate the side portions of said stem.

15 10. In a cash register, the combination of an indicator having a flat stem and means formed within said stem for supporting a coil spring.

20 11. In a cash register, the combination of an indicator having a flat stem, an aperture formed therein, and oppositely disposed projections provided within said aperture.

25 12. In a cash register, the combination of a plurality of liftable indicators, an indicator supporting bar, an operating mechanism, means controlled by the operating mechanism for retracting and then releasing the indicator supporting bar, a latch for holding the released indicator bar, and means controlled by the operating mechanism for dis-
30 abling the latch.

35 13. In a cash register, an indicator having a stem, a plurality of slots in said stem, a holding bar, lugs carried by said bar engaging in one of said slots for holding the indicator in elevated position, and a spring carried in another of said slots for initially urging the indicator to depressed position.

40 14. In a cash register, a liftable indicator having a stem, a holding bar, lugs carried by said bar, one of said lugs being adapted to engage the indicator to prevent overthrow thereof, and a spring carried by said indicator for initially urging said indicator to depressed position.

45 15. In a machine of the class described, the combination of a plurality of indicators, an indicator supporting bar, an operating mechanism, a pivoted latch member, a plate having a projecting surface actuated by said operating mechanism, a link pivoted at one end to said indicator supporting bar having a pair of projections, one of which is adapted to be engaged by the projection on said plate and the other of which is adapted to be engaged by said latch, additional means carried by said plate for releasing said latch, and means for causing said indicator supporting bar to be restored to normal position.

50 CHARLES W. GREEN.
